United States Patent

Des. 235,695
Patented July 1, 1975

235,695

CARPET

Kenneth Doyle Hill, Dalton, Ga., assignor to World Carpets, Dalton, Ga.

Filed June 1, 1973, Ser. No. 366,170

Term of patent 14 years

Int. Cl. D6—11

U.S. Cl. D92—4

The single figure is a top plan view of a carpet showing my new design, the arrows indicating a design unit, which unit repeats in regular succession.

I claim:

The ornamental design for a carpet, as shown and described.
